PORTABLE, SELF-CONTAINED TOILET

Howard A. Fulton, Perrysville, Vaughn D. Flinner, Big Prairie, Richard W. Sprang, Lakeville, and Dana D. Zody, Perrysville, Ohio, assignors to Mansfield Sanitary, Inc., Perrysville, Ohio

Filed Nov. 29, 1972, Ser. No. 310,563

Term of patent 14 years

Int. Cl. D23—02

U.S. Cl. D23—48

FIG. 1

FIG. 2

FIG. 3

FIG. 4

FIG. 5

FIG. 6

FIG. 1 is a perspective view taken from the front, top and one side of a portable, self-contained toilet showing our new design.

FIG. 2 is a top plan view thereof.

FIG. 3 is a rear elevation thereof.

FIG. 4 is another perspective view taken from the front, top and side shown in FIG. 1 showing the cover in an open position.

FIG. 5 is an elevation taken from the side opposite that shown in FIGS. 1 and 4.

FIG. 6 is a bottom plan view thereof.

We claim:

The ornamental design for a portable, self-contained toilet, as shown.
